RECIPROCATING CAN PIERCER

Paul C. Bye, Pasadena, Calif.

Application November 13, 1944, Serial No. 563,218

5 Claims. (Cl. 30—16)

This invention relates to a reciprocating can piercing apparatus.

The general object of the invention is to provide an improved apparatus for making a pouring opening and a vent opening in a can such as a milk can.

A more specific object of the invention is to provide a novel can piercing apparatus which can be made of plastic material and which includes a reciprocating member.

A further object of the invention is to provide a can piercing apparatus including a piercing member normally held spaced from the can and movable to pierce the can after the piercing member has moved through a predetermined distance.

Other objects and advantages of the invention will be apparent from the following description taken in connection with the accompanying drawing, wherein:

Fig. 1 is a side elevation, partly in section, showing an apparatus embodying the features of my invention;

Fig. 2 is a section taken on line 2—2, Fig. 1;

Fig. 3 is a fragmentary, central, sectional view

similar to Fig. 1, showing the apparatus in the

position assumed after the piercing members

have pierced a can top;

Fig. 4 is a central sectional view, showing a

modified apparatus;

Fig. 5 is a fragmentary section taken on line

5—5, Fig. 4, and

Fig. 6 is a fragmentary side elevation, showing

a modified type of piercing member.

Referring to the drawing by reference characters, I have shown my invention as embodied in a can piercing apparatus which is indicated generally at 10. As shown the apparatus includes a body 11 which is preferably made of plastic material, although it may be made of metal if desired.

The body includes recesses 12 in the bottom thereof which are arranged either side of a transversely extending partition and guide member 13 which extends from one side of a skirt 14, integral with the body, to a location diametrically opposite. The guide member 13 includes a slot 15 which opens downwardly.

The apparatus includes a piercing member indicated generally at 16. This piercing member includes a base portion 17 which is rectangular and is of substantially the same width as that of the slot 15. The base member is provided with a stem 18 which is preferably cylindrical. The stem 18 passes through a bore 19 in the body 10

and is threadedly connected to a push member 20 which is adapted to be engaged to operate the apparatus.

The body 10 is recessed as at 22 about the stem 5 and the push member is also recessed as at 23 about the stem. A spring 24 surrounds the stem and has its ends in the recesses 22 and 23. The body includes an upwardly directed cylindrical portion 25 and the push member includes a 10 skirt 26 which overlaps the cylindrical portion 25 as shown in the drawing.

The base of the piercing member has a prong 27 at one end and at the other end has a second prong 28. The prong 27 is preferably longer than 15 the prong 28 so that it will enter a can prior to the time the can is engaged by the prong 28 to thus decrease the power which would be required if both prongs pierced the can at the same time.

In operation the skirt 14 is arranged about the 20 upper perimeter of a can and then the push member 20 is pushed or struck a slight blow, causing the stem 18 to move towards the can and causing the piercing members 27 and 28 to enter the can one after the other. The 25 piercing apparatus is then removed and the contents of the can may be discharged.

In Figs. 4 and 5 I show a modification of my invention wherein some parts are designated by 30 primed reference numerals which correspond to similar unprimed reference numerals in the preceding description. In the modification, instead of extending the guide member 13 entirely across the body I provide a pair of guide members 13a at each side of the body. The guide members 13a 35 include a central slot 15a which guides the ends of the base portion 17'. The construction of the other parts is similar to that previously described.

In Fig. 6 I show a modified type of piercing member, indicated at 27''. This piercing member is arranged on a base portion 17'' and the 40 piercing member is bevelled as at 30 to provide a sharpened portion. This type of sharpened portion 30 may be substituted instead of the sharpened portion shown in connection with the 45 points 27 and 28 above.

It will be noted that in all of the modifications the piercing members are normally spaced from the end of the can. This requires that the push member 20 or the push member 20' must move 50 through a portion of its travel before the piercing members engage the can. As a result inertia is built up in the push member and piercing device and this aids materially in causing the piercing members to enter the can.

From the foregoing description it will be ap-

parent that I have invented a novel reciprocating can piercing apparatus which can be economically manufactured and which is highly efficient for its intended purpose.

Having thus described my invention, I claim:

1. A can piercing apparatus including a body having a depending cylindrical skirt thereon, a reciprocating piercing member comprising a base having a stem thereon, means on said body for guiding said member, said base having a piercing member at each end thereof, said body having a hole therein coaxial with the skirt, said stem passing through said hole, a push member on said stem, a spring normally urging said push member outwardly, said body having an upwardly directed portion thereon and said push member having a depending skirt slidable along said upwardly extending portion.

2. A can piercing apparatus including a cylindrical body having a depending skirt thereon, said body having a transversely extending diametrically arranged slot thereon, said slot opening downwardly, a reciprocating piercing member comprising a base having a stem thereon, said base being arranged in said transverse slot, said base having a piercing member at each end thereof, said body having a hole therein coaxial with the skirt, said stem passing through said hole, a push member mounted on said stem, a spring arranged on said stem between the push member and said body, said body having an upwardly directed portion thereon, said push member having a depending collar slidable along said upwardly extending portion.

3. A can piercing apparatus including a cylindrical body having a depending skirt thereon, said body having a transversely extending, diametrically arranged partition, said partition having a slot therein, said slot opening downwardly, a reciprocating piercing member comprising a base having a stem thereon, said base being arranged in said transverse slot, said base having a piercing member at each end thereof, said body having a hole therein coaxial with the skirt, said stem pass-

ing through said hole, the upper portion of said body being recessed about said stem, a push member mounted on said stem, said push member being recessed about said stem, a spring arranged on said stem between the push member and said body, the ends of said spring being disposed in said recesses, said push member having a depending collar slidable along said body.

4. A can piercing apparatus including a cylindrical body having a depending skirt thereon, said body having a transversely extending, diametrically arranged partition, said partition having a slot therein, said slot opening downwardly, a reciprocating piercing member comprising a base having a stem thereon, said base being rectangular in cross section and being arranged in said partition slot, said base having a piercing member at each end thereof and normally within the slot, one of said piercing members being longer than the other, said body having a hole therein coaxial with the skirt, said stem passing through said hole, said body having an upwardly directed cylindrical portion thereon, said body being recessed about said stem, a push member mounted on said stem, said push member being recessed about said stem, a spring arranged on said stem between the push member and said body, the ends of said spring being disposed in said recesses, said push member having a depending collar slidable along said upwardly extending cylindrical portion on said body.

5. A can piercing apparatus including a cylindrical body having a depending skirt thereon, said body having a guide member at each side, each guide member having a slot therein, a reciprocating piercing member comprising a base having a stem thereon, said base being slidable in said slots, said base having a piercing member at each end thereof, said body having a hole therein coaxial with the skirt, said stem passing through said hole, a push member mounted on said stem, and a spring arranged on said stem between the push member and said body.
